UNITED STATES PATENT OFFICE

101,846

DESIGN FOR AN EARTH MOVING DEVICE

Ellsworth W. Austin, Cedar Rapids, Iowa, assignor to La Plant-Choate Manufacturing Company, Incorporated, Cedar Rapids, Iowa, a corporation of Delaware

Application May 1, 1935, Serial No. 56,641

Term of patent 7 years

To all whom it may concern:

Be it known that I, Ellsworth W. Austin, a citizen of the United States, residing at Cedar Rapids, in the county of Linn and State of Iowa, have invented a new, original, and ornamental Design for Earth Moving Devices, of which the following is a specification, reference being had to the accompanying drawing, forming part thereof.

The figure is a view in perspective of an earth moving device showing my new design. The ap-

pearance of the opposite side of the device is substantially the same as that of the side shown. The characteristic features reside in the side plates, the bell crank arms and the side frame members in the association shown.

I claim:

The ornamental design for an earth moving device as shown and described.

ELLSWORTH W. AUSTIN.
